UNITED STATES PATENT OFFICE

WILLIAM E. LUNDGREEN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

DRIVING CONNECTION FOR LOOM DOBBIES

Application filed October 11, 1929. Serial No. 399,059.

This invention relates to a dobby loom and particularly to improvements in the construction of the mechanism for driving a dobby thereon. The number of harnesses and the width of the dobbies in such looms vary widely and it is the general object of my invention to provide driving mechanism and connections for a loom dobby which may be conveniently and quickly adjusted to adapt the same for driving a dobby of any desired width.

My invention further relates to arrangements and combinations of parts which will be hereinafter described and more particularly pointed out in the appended claims.

A preferred form of the invention is shown in the drawings in which

Fig. 1 is a side elevation of a dobby loom embodying my improvements;

Fig. 2 is a sectional rear elevation of my improved driving mechanism, taken along the line 2—2 in Fig. 1;

Fig. 3 is a detail sectional view, taken along the line 3—3 in Fig. 4;

Fig. 4 is a partial sectional side elevation, taken along the line 4—4 in Fig. 2;

Fig. 5 is a view similar to Fig. 1 but showing the parts adjusted to drive a relatively wide dobby, and

Fig. 6 is an enlarged sectional rear elevation of certain parts shown in Fig. 2.

Referring to the drawings, I have shown parts of a dobby loom including a loom frame 10 on which a dobby A is mounted in the usual manner.

The dobby shown in the drawings is of a common commercial type and includes a pattern cylinder 12 by which a pattern chain 13 is intermittently advanced. The cylinder 12 is mounted on a shaft 14 provided with a worm gear 15 intermittently rotated by a dwell worm 16 mounted on a short horizontal shaft 17 (Fig. 2). The shaft 17 is provided with a sprocket 18 engaged by a chain 20 which is continuously driven by mechanism to be described.

The dobby A is also provided with the usual rocking lever 22 having an arm 23 connected by a link 24 to a crankpin 25 fixed on

a crank arm 26, supported and rotated by a driving shaft 30.

One end of the link 24 is threaded to receive an adjustable link head 32 by which the effective length of the link may be varied as will be hereinafter described.

The shaft 30 is rotatable in a bearing 33 (Fig. 2) and is connected by gears 34 and 35 to the main crankshaft 36 of the loom. The bearing 33 is formed in a stand 40 which is pivoted to swing about the axis of the main crankshaft 36 and which is secured to the loom side 10 by clamping bolts 42. The bolts 42 extend through segmental slots 43 in the stand 40 and also extend through radial slots 44 in the loom side 10. By placing the bolts 42 in selected slots 44, the stand 40 may be secured in any desired angular position. A bolt 46 extends through a slot 48 in the lower end of the stand 40 and provides an additional securing means therefor.

With this construction, the crankshaft 30 may be swung forward or rearward relative to the loom frame 10 to such a position as will properly locate the crankshaft with reference to the rock arm 23 for a dobby of any desired width. After the crankshaft is thus located, the length of the link 24 may be correspondingly adjusted.

The crankshaft 30 is also provided with a sprocket 50, effective to drive the sprocket chain 20 previously described. The chain 20 is also engaged by an idle sprocket 52 mounted on a stud 53 secured in a gear guard 60.

The guard 60 comprises side portions 62 and a front portion 63 and is secured to the loom side by bolts 64 extending through slots 65 in the side portions 62 and through additional slots 66 in the loom side 10. The stud 53 extends through an arcuate slot 70 in the cover portion 63 of the guard 60.

With the construction thus described, the crankshaft 30 may be swung about the axis of the shaft 36 to accommodate a dobby A of any desired width and the stand 40 may be secured in position by the bolts 42 and 46. The gear guard 60 may then be adjusted and secured by bolt 64 and the idle sprocket 52

may be adjusted in the slot 70 to engage the chain 20 and take up the slack thereof.

I am thus able to provide a positive driving connection between the main crankshaft 5 36, the horizontal dobby shaft 17 and the rocker arm 22, regardless of the width of the dobby, which may vary all the way from twelve to thirty harnesses.

By this construction, the adaptation of the 10 loom to dobbies of different widths is facilitated and the number of necessary patterns and reserve parts is greatly reduced, as a single set of parts provides driving connections for dobbies of any desired width.

15 Having thus described my invention and the advantages thereof, I do not wish to be limited to the details herein disclosed, otherwise than as set forth in the claims, but what I claim is:—

20 1. In a dobby loom having a loom side and a main driving shaft, in combination, a crankshaft geared to said main shaft, driving connections from said crank shaft to said dobby, a bearing for said crankshaft, a stand for said bearing angularly adjustable about the axis of said main driving shaft, and means to secure said stand to said loom side.

25 2. The combination in a dobby loom as set forth in claim 1, in which the crankshaft is connected to the dobby by a link and in which said link is provided with means whereby its effective length may be variably adjusted.

30 3. The combination in a dobby loom as set forth in claim 1, in which a gear guard is provided, said guard being adjustable to any selected position of said crankshaft and bearing stand, and in which means is provided for securing said guard in adjusted position.

35 4. The combination in a dobby loom as set forth in claim 1, in which the crankshaft is connected to the dobby by a sprocket chain and in which an idler wheel is provided for taking up the slack in said chain.

40 5. The combination in a dobby loom as set forth in claim 1, in which a series of slots is provided in the loom side and in which clamping bolts are inserted in said slots to secure the bearing stand in a selected angular position.

45 50 6. In a loom, a dobby having a rotating member, a main driving shaft, and geared rotating driving connections from said shaft to said dobby, said connections being adjustable in length and variable in angle of application between said driving shaft and said rotatable dobby member and thereby effective to drive dobbies of different widths.

60 65 7. In a loom, a dobby having a pattern cylinder, a shaft connected to drive said cylinder, a sprocket on said shaft, a main driving shaft, an intermediate shaft geared thereto, a bearing for said intermediate shaft angularly adjustable about the axis of said main shaft, a sprocket on said intermediate shaft, a chain connecting said two sprockets, and

means to take up slack in said chain as the position of said intermediate shaft is selectively adjusted.

70 8. In a loom, a driving shaft, a warp controlling mechanism, a driving pinion on the shaft, a gear meshing therewith, a radius arm concentric with the shaft and movable to a plurality of angular positions relatively thereto, the gear being mounted on and moving with the radius arm and meshing with the pinion in all angular positions, and a connector between the gear and the controlling mechanism.

75 9. In a loom, a plurality of harness controlling devices, an actuator adapted to be operatively related to any one of said devices, said actuator being capable of assuming different positions depending upon the number of devices, a driving shaft, and connections between the actuator and the shaft movable relatively to a loom side to assume different positions dependent upon the location of the actuator.

80 10. In a loom to operate with any one of a plurality of harness controlling mechanisms 90 of different sizes, a driving shaft, a frame supporting the shaft and mechanism, a train of devices to communicate power from the shaft to the mechanism, and means to hold a portion of said train in a plurality of positions, 95 dependent upon the size of the harness controlling mechanism, the train being operatively connected to the shaft for all positions of the said portion thereof.

95 In testimony whereof I have hereunto affixed my signature.

WILLIAM E. LUNDGREN.
